Primary Examiner — Messina L Smith*Assistant Examiner* — Haley K Schnebele(74) *Attorney, Agent, or Firm* — Jose Cherson Weissbrot(57) **CLAIM**

The ornamental design for a car mug, as shown and described.

DESCRIPTION

FIG. 1 is a first perspective view of a car mug showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the car mug thereof.

The broken lines shown in the drawings depict portions of the car mug that form no part of the claimed design.

1 Claim, 9 Drawing Sheets(56)
